(57) **CLAIM**

The ornamental design for a scented mask, as shown and as described.

DESCRIPTION

FIG. 1 is a left front perspective view of a scented mask showing my new design;

FIG. 2 is a right front perspective view thereof;

FIG. 3 is a front view thereof;

FIG. 4 is a back view thereof;

FIG. 5 is a right view thereof, whereby the left view is a mirror image thereof;

FIG. 6 is a bottom view thereof;

FIG. 7 is a top view thereof; and,

FIG. 8 is a rear perspective view thereof shown in a state of use.

The broken lines included in the figures illustrate parts of the article and form no part of the claimed design. The broken lines in FIG. 8 showing a banana shape and disc represent environmental subject matter and form no part of the claimed design.

1 Claim, 7 Drawing Sheets(56)
